CATCH-CORD ELIMINATOR

Alphonse Ballard and Octave B. Caron, East Brooklyn, Alfred Theroux, Moosup, and Ernest Malo, East Brooklyn, Conn., assignors to Powdrell & Alexander, Inc., Danielson, Conn., a corporation of Massachusetts

Application June 12, 1940, Serial No. 340,100

9 Claims. (Cl. 139—116)

This invention relates to mechanical devices used on looms to engage each successive pick of filling at the selvages of the fabric so as to prevent the loops of filling at the ends of each pick from being drawn inward beyond the desired line of extent of the selvages. As they perform the same function as the extra warps often employed at the selvages as catch-cords, they are commonly known as catch-cord eliminators.

An object of the present invention is to provide a novel and improved catch-cord eliminators having advantages over prior devices in simplicity and ease of manufacture, installation, and adjustment, in long life and reduced wear, and in being able to work farther back from the fell without coming into collision with the reed than prior devices. Another object of the invention is to provide new and improved means for rendering the devices automatically inoperative at predetermined times and for any desired duration, and thereafter to restore them to operation at the desired moment.

To these ends, the invention comprises catch-cord eliminators adapted for easy attachment to the temples which hold the fabric stretched widthwise, employing a hook, point, or other filling-loop-engaging member which is slidably mounted on its supporting parts connected to the temple instead of being pivotally mounted thereon, normally actuated by the lay, each time it beats up a pick of filling, to release the filling-loop, and in certain cases operatively connected with parts of the shuttle-box motion so as to be automatically retracted forwardly of the loom to an extent where it is clear of all parts traveling with the lay.

Hooks or other filling-loop-engaging devices of prior construction have been as a rule mounted by means of a fixed pivot on the temple, and hence have been seriously limited in their rearward reach because their movement has been mainly in an up-and-down direction and with so slight a component of motion forwardly of the loom in releasing the filling that they strike the reed if allowed to extend to any substantial distance rearward of the fell. Yet the weft extending from the edge of the fabric to the shuttle-box always slants rearwardly as the lay recedes and the filling-engaging hook moves rearward into position to engage the filling. If the pick of filling to be engaged is interwoven with the warps only at a point spaced some distance inwardly from the selvage, as in the case of a figure weft running from a figure that is set back from the edge of the cloth, its spaced relation

to the fell compels the eliminator to reach rearward considerably beyond the fell into territory traversed by the advancing reed in order to intercept the pick of figure weft. This cannot be done with a member swinging as hitherto on a fixed pivot on the temple. But a finger or hook sliding fore-and-aft in the loom, or one mounted on a pivot which itself moves fore-and-aft the loom with respect to the temple, can be made to reach as far back as is ever needed in practice, in order to make sure of engaging the free outward portion of each pick of weft terminating at its side of the loom.

Thus, our improved catch-cord eliminators in their basic concept comprise a filling-engaging wire sliding fore-and-aft the loom through an eye in a support on each loom temple or other properly located base at each side of the loom, such wire extending rearwardly and downwardly to reach below the warps at the rear of the fell, and having a reverse bend at its forward end, to which is connected either rigidly or loosely a suitable member extending rearwardly above the wire to be struck by a part on the reed cap and thus moved forwardly to retract the wire upwardly and forwardly in a vertical plane so as to release the pick of weft which it had intercepted.

Since the improved device is especially adapted for use in holding outwardly the terminal loops of figure weft, the action of the devices may be suspended to save unnecessary wear and tear thereon during the insertion of the ground wefts in weaving fabrics in which the figures are spaced apart lengthwise of the fabric. Simple means is provided for such suspension of action by the invention through attaching a flexible connection or other lost-motion retractor link to the reverse bend of the wire finger or to the reed-cap-engaging member, and coupling this link to the lifting lever or other parts of the box-motion mechanism so as to retract the filling-engaging wire to a position above the warps and the actuator therefor to a position forward of the travel of the reed-cap, whenever the shuttle or shuttles carrying the figure weft are rendered inactive through change of the shuttle-boxes.

Other aims of the invention, and the manner of their attainment, are as made plain herein-after.

Illustrative embodiments of the invention are shown in the accompanying drawings, in which

Fig. 1 is a side elevation of certain of the parts at the front of a box-motion loom, showing the

devices of the invention in working relation thereon.

Figs. 2, 3 and 4 are respectively a right-hand elevation, a left-hand elevation, and a plan view, of the catch-cord eliminator shown in Fig. 1, mounted on the usual loom temple.

Figs. 5, 6 and 7 are corresponding right-hand elevation, left-hand elevation, and plan views of an alternative form of the invention.

The catch-cord eliminator of Figs. 1 to 4 comprises a filling-engaging point 1 formed on the downturned rearward extremity 3 of a continuous rod or wire 5 having a level extent 7 passing over the pod 9 of the temple and a contiguous upwardly slanting section 11 which adjoins a straight and level shank-portion 13 extending through spaced apertures 15, 17, in the opposite obliquely upturned ends of a support 19 affixed to the shelf 21 at the inward side of the temple by the means of one of the screws 23 which hold the temple to its mounting base 25, a slot 27 being provided to admit of fore-and-aft adjustment of support 19.

Rearward guide aperture 15 is an eye, with which the inclined portion 11 of the wire 5 cooperates as a cam to lift the entire rearward end of the wire 5 into the dotted-line position shown in Fig. 3 as the wire is moved forward with respect to its support 19. To impart such forward movement, the wire is bent reversely at 28 and extended rearwardly vertically above the portions 11, 13, its rearward end being offset upwardly from the portion adjacent bend 28 to bring it to the level of the reed-cap 29 of lay 31 of the loom. The extreme rearward end of this vertically offset portion is bent around as indicated at 33 to form a striker to be engaged by a suitable pad 35 applied to the front face of reed-cap 29. As the lay beats up, the impact of pad 35 against end 33 slides the whole wire forwardly into the position shown in dotted lines in Fig. 3, lifting the point 1 above the warps 37 and retracting it forward of the extreme travel of the reed. The aperture 17 in the forward end of support 19 is in the form of a slot open at the upward end of the upturned portion in which it is formed.

To return the wire 5 to its full-line position in which it engages the loops of filling, an expanding spring 39 is confined on the shank 13 between a washer 41 engaging the rearward surface of the upturned forward end of support 19 and a collar 43 adjustably fixed on shank 13 by set-screw 45.

The rearward travel of the wire under the impulsion of spring 39 is limited by a stop member 47 looped around the reverse bend 27 forward of slot 17, engaging the front face of the upturned portion of support 19 in which such slot is formed to limit rearward travel.

This stop member 47 is conveniently formed with hooked extremities so as to serve also as means for attaching the retractor strap or link 49, which pulls the wire 5 into inoperative position. This retractor strap is attached at its forward end to an eye in the upper end of an arm 51 fixed on a rockshaft 53 pivoted in suitable bearings 55 on brackets 57 bolted to the front edges of the loom sides 59 at each side of the loom. One end of rockshaft 53 has an arm 61 integral or fixed thereon which has a cranked end-portion 63 located above the forward end of lever 65 of the change-box-motion which lifts and lowers the shifting shuttle-boxes 67 in accordance with the requirements of the figures being woven. Thus, whenever the shuttle or shuttles containing the figure weft are lowered into working relation,

arm 61 is left unsupported, dropping down and allowing arm 51 to rest against the breast beam or adjacent parts, thus relaxing the tension on strap or link 49 and permitting the spring 13 to cause the wire 5 to assume the full-line position of Fig. 3, and to be pushed into the dotted-line position of such figure each time the lay beats up. When the boxes are again lifted to bring up the ground weft shuttle to race level, the forward end 10 of box-lever 65 contacts and lifts the adjacent end of arm 61 retracting the wire 5 into its protracted inoperative position until the figure weft again comes into use.

The alternative form of the invention shown in Figs. 5, 6, and 7 employs an actuator 67 from which is supported the weft-engaging wire 69, the actuator being a flat metal strip pivoted at its lower end on a bolt 71 fixed through a suitable hole in the vertical web 73 of the temple shank, the forward end of wire 69 being bent into an eye 20 which is pivotally attached by bolt 75 to an intermediate point in the length of actuator 67. The free upper end of part 67 is twisted into parallel with the reed-cap and rolled over as indicated at 77 for engagement by the pad 35 on the reed-cap. The support 19 for these parts is fixed to the temple pod by the usual cap-screw 81 which holds the top of pod 9 in place, the rearward end 83 of the support being turned up and provided with an eye 85 guiding the wire 69 in its sliding movement therethrough backward and forward in the loom. The forward end of support 19 is twisted 90° to admit of being interposed between actuator 67 and the web 73 of the temple shank, and has a tongue 87 cut away and twisted out of the vertical plane into the path of actuator 67 to engage its rearward edge and serve as a stop limiting rearward swing of the actuator. A contracting spring 89 anchored by means of a hole in part 83 pulls rearwardly on actuator 67 to hold the actuator normally against its stop 87 and the filling-engaging wire 89 extended down through the warps. The same type of means 91, engaged through a hole in the actuator 67, is employed to connect the device with the strap of retractor mechanism analogous or identical with that shown in Fig. 1, to render the device periodically inoperative when not needed.

While we have illustrated and described certain forms in which the invention may be embodied, we are aware that many modifications may be made therein by any person skilled in the art, without departing from the scope of the invention as expressed in the claims. Therefore, we do not wish to be limited to the particular forms shown, or to the details of construction thereof, but

What we do claim is:

1. A catch-cord eliminator for looms having a lay and a reed-cap on the lay, comprising in combination a support having an eye in its rearward end, a filling-engaging wire mounted for sliding movement fore-and-aft the loom through such eye, extending rearward and downward to reach below the warps at the rear of the fell, and having a reverse bend at its forward end, and means in connection with the reverse bend extending rearward above the wire to be struck by a part on the reed-cap and moved to retract the wire upwardly and forwardly in a vertical plane.

2. A catch-cord eliminator for a loom having a lay, comprising in combination a support having an eye at its rearward end and a slot at its forward end, a filling-engaging finger sliding in

such eye and having a reverse bend sliding in the said slot, and an integral portion extending rearwardly above the eye into the path of travel of a part on the lay.

3. A catch-cord eliminator for looms having in combination spaced guides, a finger sliding in such guides having a down-turned rearward filling-engaging extremity and a bent portion doubled back on itself which slides through a guide, and means reciprocating the finger back and forth in the guides.

4. A catch-cord eliminator for looms having a lay, having in combination a member engaging the working filling at a point in its length between its shuttle and the cloth, means supporting such member for movement fore-and-aft the loom, engaging the member at spaced points only in its length, means moving the member forwardly and backwardly in timed relation to the movements of the lay, and cam means on the member engaging with one of the guides to lift the rearward end of the member as the latter is moved forwardly.

5. A catch-cord eliminator for looms having in combination a filling-engaging member having a reverse bend at its frontward end, supporting means holding such bend disposed in a vertical plane with capacity for sliding movement fore-and-aft the loom, means within the bend at the frontward side of the supporting means limiting rearward movements of the member, means causing forward and rearward movement of the member, and cam means in connection with the member lifting and lowering its rearward end in the course of its respective forward and rearward travel respectively to release and to engage the working filling at a point in its length between its shuttle and the fabric.

6. A catch-cord eliminator for change-box looms having a lay, comprising in combination a member engaging the working filling at a point in its length between its shuttle and the cloth, lay-operated means making the member periodically disengage and reengage the filling, a rock-shaft, a lost-motion connection between the latter and the member, and connections between the change-box mechanism and the rockshaft rotating the latter and thereby retracting the

member out of engagement with the filling to suspend the periodic action produced by the lay.

7. A catch-cord eliminator for change-box looms having a lay, having in combination a member engaging the working filling at a point in its length between its shuttle and the cloth, means actuated by the lay retracting such member from the filling as the lay beats up and releasing it for engagement by the filling as the lay recedes, and means including a rockshaft actuated solely by the change-box-operating mechanism also retracting the filling-engaging member and holding it out of actuation by the lay.

15 8. A catch-cord eliminator for change-box looms having a lay, having in combination a member engaging the working filling at a point in its length between its shuttle and the cloth, means actuated by the lay retracting such member from the filling as the lay beats up and releasing it for engagement by the filling as the lay recedes, a rockshaft additional to such means, an arm on the latter engaged by a part on the change-box motion to rock the rockshaft when the boxes are shifted, and connections between the rockshaft and the filling-engaging member retracting the latter to an extent rendering the lay inoperative to actuate the filling-engaging member.

20 9. A catch-cord eliminator for looms having a lay, having in combination a support, a lever having one of its extremities pivoted on the support, and its other extremity yieldingly held in a position to be struck by a part on the lay as the latter beats up, a pivot on the lever intermediate the point of pivotal support of the lever and the extremity struck by a part on the lay, a filling-engaging member pivotally mounted by one of its ends on the intermediate pivot, guide means 30 on the support through which the member slides endwise as the lever is actuated by the part on the lay to place its rearward extremity alternately below and above the warps, and means yieldingly urging the lever toward the lay.
